(57) **CLAIM**

The ornamental design of electric drive unit, as shown and described.

DESCRIPTION

FIG. 1 is a perspective view of an electric drive unit showing my new design;

FIG. 2 is a rear view thereof;

FIG. 3 is a left side view thereof;

FIG. 4 is a top view thereof;

FIG. 5 is a right side view thereof;

FIG. 6 is a bottom view thereof;

FIG. 7 is a front view thereof;

FIG. 8 is a perspective view of another embodiment of an electric drive unit showing my new design;

FIG. 9 is a rear view thereof;

FIG. 10 is a left side view thereof;

FIG. 11 is a top view thereof;

FIG. 12 is a right side view thereof;

FIG. 13 is a bottom view thereof; and,

FIG. 14 is a front view thereof.

The broken lines in the drawings depict portions of the electric drive unit that form no part of the claimed design.
